MULTITOP TABLE

Raphael Alexander, New York, N. Y.

Application July 3, 1934, Serial No. 733,560

3 Claims. (Cl. 311—17)

This invention relates generally to tables, and more specifically to multi-top tables.

The main object of the invention is the provision of a table having a top surface divided into an upper and lower deck, the upper deck being confined to a single purpose such as a card playing surface while the lower deck is utilized for ash trays, drinks, score cards and other social concomitants incidental to game playing.

Another object of the invention resides in the provision of structure whereby a table is provided with spaced decks, the upper being collapsible upon the lower, and wherein the spaced relationship affords room for the storing and positioning of objects not essential for the actual playing of the game, such as bridge, upon the upper deck.

A further object of the invention resides in the provision of structure whereby a table provided with spaced decks is collapsible in a way whereby the lower deck proximate the edges thereof serves as a perimetric flange for the upper and playing deck to enable a player to more easily pick his or her cards from the edges of the playing deck.

An incidental object of the invention resides in the economy of structure and the ease with which an ordinary bridge table is convertible to the structure herein, the object of the invention.

These objects and other ends and advantages of the invention will hereinafter appear in the progress of this disclosure and as pointed out in the appended claims.

Accompanying this specification is a drawing showing a preferred form of the invention and wherein corresponding reference characters designate corresponding parts throughout the several views.

Figure 1 is an elevational view showing the table top in collapsed position.

Figure 2 is a view in plan of Figure 1.

Figure 3 is an elevational view of the invented structure in a preferred form showing the upper deck in elevated position and showing the usual 45 collapsible legs in a table commonly known as a bridge table.

Figure 4 is a sectional view longitudinal of the linking structure connecting the upper and lower deck when the links are in collapsed position, said sectional view being along the axis of said links.

Figure 5 is a sectional view along the line 5—5 of Figure 3 with the links thereof partially outstretched.

55 In accordance with the invention and in ac-

cordance with the accompanying drawing, numeral 10 designates the upper surface of a table, the said surface being provided with the usual side walls 10' if preferable. Numeral 11 designates a collapsible superposing surface with 5 the usual side walls 11' if preferable, said surface 11 forming an upper deck in relation to surface 10 and having a perimeter of any geometric shape inwardly offset from the perimeter of surface 10. The surface 10 or lower deck of 10 the table is provided with legs in the conventional manner, the legs being designate by numeral 12 and pivotally affixed to the side walls 10' by links 13. It is of course understood that the invented table may be constructed without the 15 use of leg portions altogether and be adapted to be placed upon another table.

The upper deck or surface 11 on the under side thereof is provided with parallel strips of material such as wood 20 for pivotal affixation thereto of upper link members 15, said link members 15 being pivotally connected to link members 14. Links 14 are affixed to the upper surface of lower deck 10 by a pivot 23 extending through a bracket 21, said bracket 21 being affixed to the upper surface of lower deck 10. At 20 the point of affixation of bracket 21, the under surface of lower deck 10 is provided with parallel and longitudinal strips of material such as wood 25 for purposes of receiving the affixing screws of bracket 21.

It will be seen that the upper and lower decks 11 and 10 are controlled in relative spaced positions by four linking units, links 14 of each unit being provided with opposite and rounded tenon members 18 on each side of pivot 16, while links 15 of each unit are provided with corresponding mortises 19 therefor. It is preferable that each linking unit when completely outstretched by hand effectuate a spacing between the upper and lower decks sufficient to permit the placing or storing of glasses, ash-trays, food receptacles and the like therein. In outstretched position tenons 18 and mortises 19 of each linking unit afford safety catches for the maintenance of said position, while the same relationship exists when the linking structure is in collapsed position. In collapsed position of upper and lower decks 11 and 10 respectively, the side walls 11' of upper deck 11 touch the upper surface of lower deck 10 45 thereby obscuring from view brackets 21.

I wish it distinctly understood that the embodiment of the invention encompasses the use of any suitable material in construction, encompasses all desirable shapes and integration and dupli-

tion of structures. Moreover, it is understood that minor changes and variations in the particular structure of parts may be resorted to without departing from the spirit of the invention and 5 without departing from the scope of the appended claims.

I claim:

- 10 1. In a table having an integral and fixed top member, an extensible upper platform therefor having reinforced strips on the underside thereof and situated adjacent the two opposite edges of the said upper platform the said upper platform having reduced dimensions relative to the top member, four pairs of cross links rectangularly arranged, each pair of cross links being pivoted at the crossing thereof and wherein the upper link adjacent its end is pivotally secured to the reinforced strip and the lower link adjacent its end is pivotally secured to the top member and means to secure the links in up- 10 right and collapsed position.
- 15 2. In a table having an integral and fixed top member, an extensible upper platform therefor having reinforced strips on the underside thereof

and situated adjacent the two opposite edges of the said upper platform the said upper platform having reduced dimensions relative to the top member, four pairs of cross links rectangularly arranged, each pair of cross links being pivoted at the crossing thereof and wherein the upper link adjacent its end is pivotally secured to the reinforced strip and the lower link adjacent its end is pivotally secured to the top member and means to secure the links in up- 5 right and collapsed position.

3. In a table having an integral and fixed top member, an extensible upper platform, the said upper platform having reduced dimensions relative to the top member, four pairs of cross-links 15 rectangularly arranged, each pair of cross-links being pivoted at the crossing thereof and wherein the upper link adjacent its end is pivotally secured to the underside of the said extensible upper platform and the lower link adjacent its 20 end is pivotally secured to the top member.

RAPHAEL ALEXANDER.
